UNITED STATES PATENT OFFICE.

SIEGMUND LOEWE, OF BERLIN, GERMANY, ASSIGNOR TO WESTERN ELECTRIC COMPANY, INCORPORATED, OF NEW YORK, N. Y., A CORPORATION OF NEW YORK.

RECEIVING APPARATUS FOR HIGH-FREQUENCY SIGNALING.

Application filed March 19, 1921. Serial No. 453,846.

To all whom it may concern:

Be it known that I, SIEGMUND LOEWE, a citizen of the German Republic, residing at Berlin, Germany, have invented certain new and useful Improvements in Receiving Apparatus for High-Frequency Signaling (for which I have filed application in Germany, Feb. 23, 1920), of which the following is a full, clear, concise, and exact description.

10 The present invention deals with a specially simple and convenient arrangement for producing heterodyne reception in telegraphy with or without wires. An advantage of the present method is that a special local 15 generator circuit is avoided and only one operation is needed to change the tuning and the frequency of the locally produced waves. There are special advantages with reference to the use of energy which are 20 conveniently offered by the present arrangement. The system is well adapted to those types of receivers employing a local source of waves of a frequency in the neighborhood 25 of the received waves.

Two possible systems employing the invention are shown in Figs. 1 and 2.

Fig. 1: 1 is a frame or loop antenna with tuning condenser 2. 3 is the anode of an electron discharge tube T, 4 its grid, 5 the 30 incandescent cathode, 6 the heating battery. The source of potential for the tube is connected between the terminals 7 and 8. By this means locally generated waves are applied to the input circuit of the tube 9 through the antenna. The terminals of condenser 2 are connected to the grid and cathode of an amplifier tube 9, in whose anode circuit there is a battery and may be a high resistance 10, from which a lead is 40 connected to the grid of the next amplifier tube 11. A blocking condenser and a telephone 12 are connected in the anode circuit of this tube. The necessary detecting action will take place in the tube 9 or the tube 11.

45 A particular advantage of this arrangement is that the vacuum tube need only be connected to a part of coil 1 so that the received energy in the antenna 1 can be conducted to tube 9 with as little loss as possible. 50 In other words only a portion of the voltage across the antenna which results from received waves is impressed upon the device T.

Fig. 2 shows another possible application. A tube 13 having suitable circuits for generating oscillations is connected with the

frame antenna and has the usual feed back, while the rest of the arrangement is the same as in Fig. 1. The loop antenna 1 comprises inductance 13 and 14 in series with the variable condenser 2. A coil 15 coupled to the coil 14 provides a feed-back connection for the oscillation generating tube 13. If the condenser 2 is varied to change the circuit to receive another wave length the frequency of the locally generated oscillations is changed approximately the same amount so the beat or difference frequency remains approximately the same.

The novel features believed to be inherent in the invention are defined in the appended claims.

What is claimed is:

1. A receiving system comprising a loop antenna, a receiving electric discharge tube connected across an element of said antenna, 75 inductance in said antenna, and an electric discharge device for supplying locally produced oscillations to said antenna connected across a portion of said inductance.

2. A receiving system comprising a loop 80 antenna, a circuit for translating received signals connected to said antenna, a device for supplying locally produced oscillations to said antenna, and means connecting said antenna to said device whereby only a portion of the electromotive force developed in said antenna is applied to said device.

3. A receiving circuit comprising a space 85 discharge device functioning as an oscillation generator, a loop antenna having an impedance element connected across two electrodes of said device, a feed-back connection from said antenna to said device, and in addition to said device a translating circuit for received signals coupled to said antenna. 95

4. A receiving system comprising a loop antenna, a space discharge device having appropriate circuits connected thereto whereby said device functions as an oscillation generator, said circuits including said antenna, reactance means in said antenna, a portion only of said reactance means being coupled to said device in a manner effective to transfer energy from said antenna to said device, and a reception circuit coupled to said antenna. 100

In witness whereof, I hereunto subscribe my name this ninth day of February A. D., 1921.

Dr. SIEGMUND LOEWE,
